UNITED STATES PATENT OFFICE.

PETER HAYDEN, OF NEW YORK, N. Y.

DESIGN FOR BUCKLES.

SPECIFICATION forming part of Design No. 11,640, dated February 3, 1880.

Application filed November 10, 1879. Term of patent 14 years.

To all whom it may concern:

Be it known that I, PETER HAYDEN, of New York, in the county and State of New York, have invented and produced a new and original Design for Harness-Buckles, of which the following is a specification, reference being had to the accompanying drawing, making part of the same.

The figure is a front or plan view of my improved buckle.

A represents the body of the buckle, having a cross-bar, B, at the rear portion. C is an added cross-bar, united with the extending sides d, forming an oblong aperture in this portion of the buckle.

The cross-bars B C are raised up flush with the upper surface of the body of the buckle, and are made to have the same finish.

I claim—

The buckle having at the rear portion the parallel cross-bars B C, with the upper surface of each raised up and finished flush with the sides of the buckle, as a new element of ornamentation.

PETER HAYDEN.
